UNITED STATES PATENT OFFICE.

CHARLES V. HENRY, OF PITTSBURG, PENNSYLVANIA, ASSIGNOR OF ONE-HALF TO ASAPH T. ROWAND, OF SAME PLACE.

GAS-FURNACE.

SPECIFICATION forming part of Letters Patent No. 373,018, dated November 8, 1887.

Application filed October 28, 1886. Serial No. 217,382. (No model.)

To all whom it may concern:

Be it known that I, CHARLES V. HENRY, residing at Pittsburgh, in the county of Allegheny and State of Pennsylvania, a citizen of the 5 United States, have invented or discovered certain new and useful Improvements in Gas-Furnaces, of which improvements the following is a specification:

In the accompanying drawings, which make 10 part of this specification, Figure 1 is a central vertical section of my improved gas-furnace. Fig. 2 is a horizontal section on the line *x* *x*, Fig. 1. Fig. 3 is a perspective view, on an enlarged scale, of one of the segmental blocks.

15 The invention herein relates to certain improvements in the form or construction of furnaces whereby gaseous fuel may be employed in melting the metal charge. Great difficulty has heretofore been experienced in melting 20 metal in cupola-furnaces by means of gaseous fuel, as the metal when it becomes soft and pasty sinks down and fills the openings through which the gas and air are admitted, thereby stopping the flow of gas into the cupola. The 25 stoppage of the flow of gas will result in a chilling of the metal, thereby necessitating the tearing down of a portion or all of the cupola to remove the chilled mass.

The object of the invention herein is to so 30 construct the furnace as to provide passages or flues for the flow of gas, such flues being so located with reference to the support for the charge that they will not be liable to become clogged or stopped by molten metal; and, in 35 general terms, the invention consists in the construction and combination of parts substantially as hereinafter more fully described and claimed.

The furnace or cupola 1 is of the usual form 40 and construction, having the crucible 2 at its lower end, the bottom of said crucible being formed by the drop-door 3, said door being lined on the inner side with fire-clay, as shown. At the upper edge of the crucible is formed a 45 shoulder or ledge, 4, on which are supported the wedge-shaped blocks 5, having their inner edge cutaway, as shown, thereby forming, when said blocks are arranged within the cupola, an arched cover for the crucible 2. One side of 50 each block is cut away for a portion of its width,

thereby forming, when the blocks are placed together in the cupola, passages 6, connecting the crucible and the upper part of the cupola. A shallow basin is formed in the upper sides of the blocks by inclining the upper surface of 55 each block from its outer perimeter to its inner end. The central opening, formed by the excised ends of the segmental blocks 5, when placed within the furnace, is closed by a fire-clay plug, 7, as shown in Fig. 1. The fire-bricks 60 forming the inner lining of the furnace are so cut or otherwise shaped on their inner surfaces as to form a series of longitudinal grooves, 8, around the inner wall of the furnace. These grooves 8 extend down behind the blocks 5 to 65 a metal or fire-clay ring or annulus, 9, incorporated with the lining of the furnace at a point about midway of the height of the blocks, and provided on its inner face with a groove, 10. A pipe, 11, connects the groove 10 with 70 the mixing-chamber 12, into which gas and air are introduced by suitable pipes in suitable quantities and under suitable pressure. The groove 10 is placed in communication with the crucible 2 by means of notches 13 cut through 75 ribs 14, formed by cutting away a portion of one side of the blocks 5, as above stated.

In using my improved furnace the pig metal or ore to be treated is placed upon the perforated bridge or partition formed by the blocks 80 5. Combined gas and air are then admitted or forced into the groove 10, from which it passes by the notches 13 and passages 6 into the crucible and also into the part of the furnace above the bridge or partition formed by 85 the blocks 5, by the grooves 8, and by the passages 6. In this manner the charge on the blocks is subjected to a direct impact of the flames, not only at the sides, but also at the bottom. As the metal begins to soften and 90 melt, it will flow down the sides of the shallow basin formed by the inclined upper surfaces of the blocks, and as soon as it becomes sufficiently fluid will run down the passages 6 into the crucible. In case the metal should, while in a 95 pasty or semi-molten state, settle down upon the blocks and close and partially close the passages 6, sufficient gas will be supplied by the grooves 8 to complete the melting operation, assisted by the intense heat generated in the 100

crucible. The inclined sides of the basin in the uppersurface of the blocks 8 will cause the metal to flow toward the center of the furnace and thereby keep the grooves 8 from being clogged by molten or semi-molten metal.

5 Although I have described my improvements in connection with a cupola or melting furnace, they are equally applicable to a blast-furnace for the reduction of ores.

10 I claim herein as my invention—

15 1. A cupola-furnace having a horizontal partition, thereby forming a chamber at the lower end of the cupola, said chamber serving as a crucible for the reception of molten metal and as a combustion-chamber, said partition being provided with a series of passages for the discharge of molten metal into the crucible and the passage of the products of combustion from the crucible, in combination with a series of 20 tuyeres for conducting and discharging combined gas and air into the crucible, substantially as set forth.

25 2. The combination, with a furnace, of a crucible formed in the lower end of the furnace, of a series of segmental blocks arranged above the crucible and serving as a support for the charge of metal, said blocks being grooved, as described, thereby forming passages leading from the crucible to the upper part of the furnace, and a

series of two or more tuyeres for conducting 30 and discharging combined gas and air into the crucible, substantially as set forth.

3. The combination, with a furnace having its inner wall grooved, as described, of a crucible formed in the lower end of the furnace, a 35 perforated partition arranged above the crucible and serving as a support for the charge, and a series of two or more tuyeres for conducting and discharging combined gas and air into the crucible and the longitudinal grooves in the 40 wall of the furnace, substantially as set forth.

4. The combination, with a furnace having its inner wall grooved, as described, of a crucible formed in the lower end of the furnace, a 45 perforated partition arranged across the furnace above the crucible and having a concaved upper surface, and a series of two or more tuyeres for conducting and discharging combined gas and air into the crucible and the longitudinal grooves in the wall of the furnace, 50 substantially as set forth.

In testimony whereof I have hereunto set my hand.

CHARLES V. HENRY.
